UNITED STATES PATENT OFFICE.

EDGAR JOSEPH DE NORMANVILLE, OF LONDON, ENGLAND.

BAND BRAKE.

Application filed August 28, 1922. Serial No. 584,790.

To all whom it may concern:

Be it known that I, EDGAR JOSEPH DE NORMANVILLE, a subject of the King of Great Britain, residing at London, England, have invented new and useful Improvements in Band Brakes, of which the following is a specification.

This invention relates to improvements in band brakes for arresting rotary movement 10 of a brake drum.

Heretofore it has been known to anchor one end of such a brake band to a fixed part and to move the other end by means of a spring or other connection. This arrangement 15 operates satisfactorily so long as the drum has a tendency or is able to rotate in only one direction but is inefficient when the direction in which the drum has a tendency to rotate is reversed.

20 This invention provides a brake band mounted and operated so that it acts efficiently on the drum when the latter rotates or tends to rotate in either direction.

The accompanying drawing shows how 25 the said invention may be conveniently and advantageously carried into practice.

In this drawing:

Figure 1 is an end view, with parts in 30 section, of a brake drum provided with a brake band mounted in accordance with this invention.

Figure 2 is a similar view of a modified 35 constructional form of the brake band mounting.

Figure 3 is a detail view of a cam bar operating lever hereinafter referred to.

Referring to Figure 1, 5 is a brake drum around which is lapped a brake band 6 the 40 ends of which are respectively secured to brake blocks 7, 7. These brake blocks may be arranged to make contact with the cylindrical surface of the drum, or as shown they may engage in a groove 8, or grooves in the periphery of the drum. Each brake block is carried by a pin or bar 9 passing 45 through a slot 10 in the block and extending between the limbs of the forked end of a corresponding lever 11 which can rock on a pivot pin 12 carried by a fixed frame part.

50 The levers 11 are moved about the pivot pins 12 by engagement with spring pressed plungers 13 arranged in alignment in guide-ways 13^a having closed ends and movable towards each other by springs 14. The 55 plungers 13 can be moved apart by wedge or cam surfaces 15 provided on opposite

sides of a longitudinally slidable bar 16, seen in transverse section in Figure 1, arranged between the proximate ends of the plungers. 60

With this construction, when the bar 16 is in a position in which the cams 15 thereon are located between the plungers 13 to hold the same separated, with the springs 14 under compression, the levers 11 are 65 moved to the positions indicated in broken lines, thereby carrying the blocks 7 out of contact with the brake drum and also slackening the band 6 so that the drum 5 can revolve freely so far as the action of the 70 brake is concerned.

If now the bar 16 is moved so that the cams are carried away from between the plungers, then the latter are moved by their springs and bring the levers 11 to the positions in which they are shown in full lines, whereby also the blocks 7 are brought into contact with the drum. Assuming the drum to be revolved in counter-clockwise direction, as indicated by the arrow, the block at 80 the right hand side of Figure 1 will, by its frictional engagement with the drum, be moved from the position indicated in broken lines to that indicated in full lines thereby tightening the brake band 6. The 85 brake block at the left hand side of Figure 1 resting against a stop or abutment 17 on a convenient part of the frame or casing enclosing the drum, acts as a fixed anchorage for the end of the brake band attached 90 thereto.

By attaching the ends of the brake band to brake blocks so as to be moved thereby, a construction is provided in which the brake band is self adjusting, for example, to take 95 up wear either of the brake band or of the drum, or to allow for expansion in the event of the drum or the band becoming overheated. Moreover, when the band is released from the drum, the weight of the 100 blocks thus left free to drop within the casing, operates to expand the band and hold it in contact with the casing so that it does not chatter or rattle.

In the event of the drum commencing to rotate in the clockwise direction the block on the right hand side is carried with the drum into contact with its abutment 17 and becomes a fixed anchorage for the end of the 110 band attached thereto. At the same time the brake band is closely applied to the drum by the pull of the block on the left

hand side of Figure 1 which is moved away from its abutment by its frictional contact with the drum 5, the slot 10 in the block moving upwardly on the pin 9.

5 In an arrangement in accordance with this invention applied to the change speed gear of an automobile vehicle wherein the gear comprises a range of band brakes operated selectively to hold corresponding 10 brake drums stationary and thereby to put into operation trains of gearing giving different velocity ratios, two or more wedge or cam bars 16 are provided and, preferably, each bar is moved singly, in turn, by a single 15 operating lever or handle. A suitable arrangement, shown in Figure 3, comprises a lever 18 having a rocking movement about a pivot pin 19 mounted in a ball or cylinder 20 mounted to turn in bearings in a 20 direction at right angles to the movement of the lever 18 about the pivot 19. Sliders 21 respectively connected to the bars 16 can be engaged singly by the lever 18 by rocking the cylinder 20, and then the lever can 25 be rocked on the pivot 19 to move the selected slider longitudinally. In addition the lever may be mounted to have a vertical movement on the pivot pin 19 so that it can be brought into engagement with other 30 sliders or wedge carrying bars either by a vertical movement alone or by combined vertical and lateral rocking movements.

In the modified constructional arrangement shown in Figure 2, the plungers 22 are 35 arranged to move on paths which intersect at right angles and the ends of the plungers have flats 23, 24 formed thereon the surfaces of which are likewise disposed at right angles and are inclined symmetrically on 40 opposite sides of the axis of the path on which the plunger moves. In this arrangement the brake blocks are omitted and opposite ends of the brake band 25 are respectively connected directly to the plungers. Wedge or cam surfaces 26 are provided on a bar 27 to act on the flats 23 on 45 the plungers and push them downwardly into their guideways against the thrust of the springs 28, to the position in which the plunger on the left hand side of Figure 2 is shown. When both plungers are in this position the brake band is slackened releasing 50 the drum.

When the wedges or cams are moved out 55 of the path of the plungers the latter are moved by their springs thereby tightening the brake band onto the drum. Then if the drum commences to rotate in either direction the band moves with the drum, the 60 plunger spring which opposes this movement is compressed whilst the other spring advances its plunger to maintain the brake band in effective contact with the drum. Assuming the drum to rotate in the direction indicated by the arrow, the spring 28

on the left hand side of Figure 2 is compressed, or the corresponding plunger is brought against the closed end of its guideway 22^a, as shown, so that a fixed anchorage is provided for this end of the brake band. 70 At the same time the spring 28 on the right hand side of Figure 2 advances its plunger and tightens the brake band on the drum so that continued rotation of this drum is prevented. 75

The bar 27 may have other wedges or cams thereon to associate the operation of the drum 5 with other drums comprised, for example in the same variable velocity ratio gearing. A bar 29 is provided to act on the flats 24 by means of wedges or cams 30 in a manner similar to that in which the bar 27 acts on the flats 23. These bars can conveniently be operated by a lever such as that shown in Figure 3. Other wedge or cam bars may also be provided, for example, a bar 31 operated by the same lever as that operating the bars 27, 29, or independently, as for example by a pedal, the wedges or cams 32 on this bar being arranged to put 80 out of operation, simultaneously, all the brake bands controlled by cams or wedges on the bars 27, 29 independently of the position of these bars. 85

What I claim is:—

1. A brake mechanism for braking a rotary drum, comprising a brake band, plungers respectively connected to opposite ends of the band, springs respectively acting on the said plungers, fixed frame parts providing bearings for the said springs, and means for moving and holding the said plungers against the action of their springs. 100

2. A brake mechanism for braking a rotary drum, comprising a brake band, independently movable plungers respectively connected to opposite ends of the band, springs respectively acting separately on the said plungers, and means for moving and holding said plungers against the action of their springs. 105

3. A brake mechanism for braking a rotary drum, comprising a brake band, spring pressed plungers operatively connected to opposite ends of the band respectively, and guideways for receiving and limiting the movement of each plunger. 115

4. A brake mechanism for braking a rotary drum, comprising a brake band, plungers operatively connected to opposite ends of the band respectively, guideways having closed ends for receiving and limiting the movement of each plunger in one direction and springs for moving each plunger away from the closed end of its guideway. 120

5. A brake mechanism for braking a rotary drum, comprising a brake band, plungers operatively connected to opposite ends of the band respectively, guideways with closed ends for receiving and limiting the 125

movement of each plunger in one direction, springs for moving the plungers away from the closed ends of the guideways, and cams for moving and holding each plunger 5 against the thrust of the corresponding spring.

6. A brake mechanism for braking a rotary drum, comprising a brake band, plungers movable in oppositely arranged guideways and operatively connected to opposite ends of the band respectively, and springs for moving the plungers towards each other in the said guideways.

7. A brake mechanism for braking a rotary drum, comprising a brake band, brake blocks respectively connected to opposite ends of the band, spring pressed plungers movable in guideways and levers for communicating motion from the said plungers 20 to the brake blocks.

8. A brake mechanism for braking a rotary drum, comprising a brake band, brake blocks respectively connected to opposite ends of the band, spring pressed plungers 25 movable in guideways, levers for communicating motion from the said plungers to the brake blocks, and a pin and slot connection between each lever and the corresponding brake block.

30 9. A brake mechanism for braking a rotary drum, comprising a brake band, brake blocks respectively connected to opposite ends of the band, spring pressed plungers movable in guideways, levers pivotally

mounted on a fixed frame part and movable 35 by means of the said plungers, a pin and slot connection between each lever and the corresponding brake block, and stops on the fixed frame part for limiting the movement of each of the brake blocks.

10. A brake mechanism for braking a rotary drum, comprising a brake band, brake blocks respectively connected to opposite ends of the band, spring pressed plungers 40 movable in guideways, levers operated by the plungers when free to move under the action of their springs to apply the brake blocks to the drum, and a pin and slot connection between each brake block and the corresponding lever.

11. A brake mechanism for braking a rotary drum, comprising a brake band, brake blocks respectively secured to the ends of 45 said band, levers for moving the brake blocks into contact with the said rotary drum, a pin and slot connection between each brake block and its lever allowing a restricted movement of the brake blocks with the drum when pressed against the latter, stops provided on a fixed frame part to limit 50 such movement of the brake blocks, spring pressed plungers operating to move the said levers to apply the brake blocks to the drum, and means for moving and holding the said plungers against the action of their 55 springs.

EDGAR JOSEPH DE NORMANVILLE.
